Atty.

UNITED STATES PATENT OFFICE.

EDWIN REYNOLDS, OF MILWAUKEE, WISCONSIN.

DISCONNECTING DEVICE FOR ECCENTRIC-RODS.

SPECIFICATION forming part of Letters Patent No. 448,259, dated March 17, 1891.

Application filed December 10, 1890. Serial No. 374,237. (No model.)

To all whom it may concern:

Be it known that I, EDWIN REYNOLDS, a citizen of the United States, residing at Milwaukee, in the county of Milwaukee and State 5 of Wisconsin, have invented certain new and useful Improvements in Disconnecting Devices for Eccentric-Rods, of which the following is a specification.

My invention relates to steam-engines, and 10 has reference more particularly to a novel construction of mechanism whereby the eccentric-rod may be readily disconnected from and connected to the wrist-plate.

In the drawings, Figure 1 is a vertical sectional view of my improved disconnecting device; Fig. 2, a horizontal sectional view on the line 2 2 of Fig. 1, and Fig. 3 a transverse vertical sectional view on the line 3 3 of Figs. 1 and 2.

20 A indicates the wrist-plate, and C an open-ended cup or socket, which is secured to the wrist-plate by means of a bolt B. Fitting into the open end of the cup C is a casting E, the periphery of which is turned smooth, so as to 25 permit the eccentric rod or stem D, which is designed to be locked to the casting E, to turn with the latter at right angles to the axis of the cup C, the latter being cut away on its upper and lower faces, as shown in Fig. 3, to 30 permit of this motion of the eccentric-rod.

The cup-shaped casting E is provided beyond the cup C with a hollow neck or extension E', in which is fitted a rod or stem F, having at its outer end a handle G, as shown in 35 Figs. 1 and 2. This rod or stem is provided with a key or stud H, which is designed to fit into a longitudinal groove or key-seat H' in the neck or extension E', as shown in Figs. 1 and 2, and the stem is further provided near 40 its inner end with an enlargement F', which serves to guide the stem in its longitudinal movements. The extreme inner end of the stem is designed to enter a hole or opening J, formed in the eccentric-rod D, as shown in 45 Figs. 1 and 2, and when the stem or pin is in engagement with the eccentric-rod and the latter locked to the casting E by means of the stud H and the groove H' the eccentric-rod will be thereby locked to the casting E.

50 A coil-spring I, bearing at one end against

the enlargement F' of the stem F and at the opposite end against the inner wall in the neck or extension E', serves to hold the stem or pin in engagement with the eccentric-rod, and to disconnect the two stems it is necessary 55 to overcome the force of the coil-spring.

When it is desired to withdraw the rod or stem F from engagement with the eccentric-rod D, the former will be pulled outward, as indicated by the dotted lines in Fig. 1, and 60 then given a slight turn, so as to bring the stud or key H out of line with the groove or slot H' and cause the said stud or projection to rest upon the outer end of the extension E' of the casting E, and thereby hold the said 65 pin or stem F out of engagement with the eccentric-rod.

Having thus described my invention, what I claim is—

1. In combination with a wrist-plate provided with a perforated socket-piece C, through which the eccentric-rod passes, a casting E, mounted within the socket and also perforated to receive the eccentric-rod, and means, substantially such as shown, for locking 75 the eccentric-rod to the casting.

2. In combination with a wrist-plate provided with a cup-shaped socket C, a casting E, fitting therein and adapted to receive the eccentric-rod, and a pin or stem F, carried by 80 the casting E and adapted to engage the eccentric-rod, all substantially as shown.

3. In combination with a wrist-plate provided with the cup-shaped socket C, perforated to receive the eccentric-rod, the casting E, fitting within the cup-shaped socket, perforated to receive the eccentric-rod, and provided also with a neck or extension having a groove H', and a pin or bolt F, adapted to engage the eccentric-rod and provided with a stud or projection H, all substantially as shown and described. 85

4. In combination with a wrist-plate provided with a cup-shaped socket C, perforated to receive the eccentric-rod, the casting E, fitting within the cup-shaped socket, perforated to receive the eccentric-rod, and provided with a neck or extension E', having a groove H', a rod or stem F, provided at its outer end with a handle and having its inner end fashioned to 95 100

engage the eccentric-rod, a spring adapted to hold the stem normally in engagement with the eccentric-rod, and a stem or projection H, carried by the stem or bolt F and working 5 within a groove H', formed in the neck or extension E', all substantially as shown and described.

In witness whereof I hereunto set my hand in the presence of two witnesses.

EDWIN REYNOLDS.
